FLYING SAUCER TOY

Jerome L. Asner, 2604 SW. 65th St. 73159, and Edward N. Campbell, 4068 NW. 61st St. 73112, both of Oklahoma City, Okla.

Filed July 5, 1967, Ser. No. 7,710

Term of patent 14 years

(Cl. D34—15)

FIG. 2

FIG. 1

FIG. 3

FIGURE 1 is a plan view of a flying saucer toy showing our new design.

FIGURE 2 is a sectional view taken along line 2—2 of FIGURE 1.

FIGURE 3 is a bottom plan view.

We claim:

The ornamental design for a flying saucer toy, substantially as shown.
